Primary Examiner — Cary M Robinson*Assistant Examiner* — Emily Anna Saunders(74) Attorney, Agent, or Firm — Goldstein Law Offices, P.C.CLAIM

The ornamental design for a set of playing cards, as shown and described.

DESCRIPTION

The sole FIGURE is a front elevational plan view of set of playing cards in accordance with the present invention. The broken lines shown in the sole FIGURE depict portions of the set of playing cards that form no part of the claimed design. Each card is of conventional thickness that forms no part of the claimed design. The rear side of each card in the set of playing cards forms no part of the claimed design.

1 Claim, 1 Drawing Sheet(56)
